(57) **CLAIM**

The ornamental design for a hammock camping chair, as shown and described.

DESCRIPTION

FIG. 1 is a front elevational view of a hammock camping chair showing my new design;

FIG. 2 is a rear elevational view thereof;

FIG. 3 is a left elevational view thereof;

FIG. 4 is a right elevational view thereof;

FIG. 5 is a top plan view thereof;

FIG. 6 is a bottom plan view thereof; and,

FIG. 7 is a perspective view thereof.

The broken lines shown in the drawings illustrate portions of the hammock camping chair that form no part of the claimed design.

1 Claim, 7 Drawing Sheets
